UNITED STATES PATENT OFFICE.

LA FAYETTE T. WEVER, OF ARRAN, FLORIDA, ASSIGNOR TO JOHN MITCHEL ANDREWS, OF ARRAN, FLORIDA, AND CHARLES M. AUSLEY, OF TALLAHASSEE, FLORIDA.

RAILWAY-RAIL JOINT.

SPECIFICATION forming part of Letters Patent No. 711,687, dated October 21, 1902.

Application filed April 18, 1902. Serial No. 103,598. (No model.)

To all whom it may concern:

Be it known that I, LA FAYETTE T. WEVER, a citizen of the United States, residing at Arran, in the county of Wakulla and State of Florida, have invented a new and useful Railway-Rail Joint, of which the following is a specification.

This invention relates to railway-rail joints, and has for its object the production of a means for uniting the adjacent ends of railway-rails in a more secure manner and with fewer parts, and consequently at a less expense, and which will also give greater strength to the joint and effectually prevent all "creeping" or longitudinal movement.

The invention consists in certain novel features of construction, as hereinafter shown and described, and specifically pointed out in the claims.

20 In the drawings illustrative of the invention, Figure 1 is a plan view. Fig. 2 is a transverse section on the line $\alpha\alpha$ of Fig. 1. Fig. 3 is a transverse section on the line $\gamma\gamma$ of Fig. 1. Fig. 4 is a perspective view of one 25 of the clamp-plates detached.

The contiguous rail ends are indicated at 10 and 11 and the ties at 12, of the usual form.

The joint will generally be long enough to 30 bridge three ties, as shown; but may be modified to embrace two ties only, if preferred.

The improved joint consists of two plates 13 14, disposed on opposite sides of the rail and formed to engage the vertical web on opposite sides next to the "head" by their upper edges 15 and 16 and having inwardly-extending lower portions 17 and 18, embracing the under side of the lower flange of the rail, as shown in Fig. 3. The plates 13 and 40 14 therefore do not contact with the rail between their upper edges 15 and 16 and the outer edges of the lower flange of the rail, as shown in Figs. 2 and 3. At their ends the plates 13 and 14 are supported by

45 chairs 19, with upwardly-extending ribs or flanges 21 22, the flanges being slightly undercut or "dovetailed" and engaging the correspondingly-inclined outer edges of the plates outside the ribs 17 18. The ribs 17 and 18 do not extend the full length of the

plates, but only between the chairs 19, so that the ends of the ribs form shoulders to limit the inward movement of the chairs. Perforations for the spikes 23 will be formed in the chairs and alined recesses will be 55 formed to receive the upper parts of the spikes, as shown, the spikes thus not only firmly securing the chairs to the ties, but also binding the rails and chairs together and preventing horizontal movement between them. 60 When the joint is arranged to bridge three ties, intermediate ears 24 will be formed on the plates 13 14 and provided with recesses for spikes, so that the plates may be secured to the central tie. By this arrangement the 65 downward pressure upon the plates 13 and 14 will cause their lower ends to be distended against the ribs 21 22 of the chairs 19, which force will cause the upper ends 15 and 16 to be forced inward in engagement with 70 opposite sides of the web of the rail, and the stronger the downward force the greater will be the "grip" imparted to the rail. The ribs 21 22 being inclined inward, as shown in Fig. 2, the plates are firmly held from any 75 upward movement. The chairs will be constructed to engage the rails and plates closely, so that considerable force will be required to drive them "home" against the shoulders formed by the ends of the webs 17 and 18, so 80 that any tendency to work loose or "rattle" will be counteracted. The ribs 17 and 18 serve a twofold purpose—first, as spreaders to keep the chairs in their proper place, and, second, as supports to the lower flange of the 85 rail and also as a support to the joint from beneath. By this arrangement all the parts are firmly joined together and held in place without the necessity for transverse bolts through the plates and rails, and all strains 90 to which the joint is subjected will bind them more firmly together, and the greater the strain the more firmly they will be gripped.

Having thus fully described my invention, 95 what I claim as new, and desire to secure by Letters Patent, is—

1. In a railway-rail joint, two abutting rails, plates disposed upon opposite sides of said rails, chairs supporting the opposite ends of 100

said plates and having inwardly-inclined ribs engaging the lower correspondingly-inclined edges of said plates, the ties supporting said chairs, apertures for the spikes 5 through said chairs, opposing recesses in said inclined ribs and in the adjacent edges of said plates and registering with said apertures, whereby the holding-spikes are adapted to lock the parts together, substantially as 10 described.

2. In a railway-rail joint, two abutting rails, plates disposed upon opposite sides of said rails, chairs independently supporting the opposite ends of said plates and having inwardly-inclined opposing ribs engaging the lower correspondingly-inclined edges of said plates, said plates having inwardly-extended ribs between and abutting upon said chairs 15 engaging the lower surfaces of the lower flanges of the rails and engaging the head of the rail at opposite sides of the vertical webs by their upper edges, substantially as described.

3. In a railway-rail joint, two abutting rails,

plates disposed upon opposite sides of said 25 rails, chairs independently supporting the opposite ends of said plates and having inwardly-inclined opposing ribs engaging the lower correspondingly-inclined edges of said plates, the ties supporting said chairs, apertures for the spikes through said chairs, opposing recesses in said inclined ribs and the adjacent edges of said plates and registering with said apertures, whereby the holding-spikes are adapted to lock the parts together, 30 inwardly-extending ribs upon said plates between said chairs and engaging the lower surfaces of the lower flanges of said rails, said plates engaging the heads of said rails on opposite sides of the vertical webs, substantially as described.

In testimony that I claim the foregoing as my own I have hereto affixed my signature in the presence of two witnesses.

LA FAYETTE T. WEVER.
